UNITED STATES PATENT OFFICE.

JOHN T. EVANS, OF UTICA, NEW YORK.

RAIL-JOINT.

SPECIFICATION forming part of Letters Patent No. 508,004, dated November 7, 1893.

Application filed December 5, 1891. Serial No. 414,159. (No model.)

To all whom it may concern:

Be it known that I, JOHN T. EVANS, a citizen of the United States, and a resident of Utica, in the county of Oneida and State of New York, have invented new and useful Improvements in Rail-Joints; and I do hereby declare the following to be a full, clear, and exact description of said invention, reference being had to the accompanying drawings, and to the letters of reference marked thereon, which form a part of this specification.

My invention relates to new and useful improvements in rail-joints, the object of the invention being to provide means for making a firm and durable jointing of the rails which will be simple and inexpensive in both construction and application.

The invention consists in certain novel features in the arrangement and construction of parts, all as hereinafter described.

In the accompanying drawings in which my invention is fully illustrated: Figure 1, is a top view of the abutting ends of the rails showing the same used with the ordinary form of bed plate. Fig. 2, is a transverse vertical sectional view, taken on the line x , x , of Fig. 1. Fig. 3, is a perspective view of a portion of a rail showing the locking bolt and the form in which it is inserted through the slot 30 in the lap portion. Fig. 4, is a perspective view of the double bolt.

Referring to the drawings by letter, A denotes the rails the opposite sides of the ends of which are formed with right angular recesses so as to overlap each other to give greater strength to the joints, requiring less of the rail-jointing devices than if the rails were square ended and at the same time retaining the same straight line of shock or jar 40 secured by square end rails.

On the cross ties B, B, of the road at the points where the ends of the rails come together, is stationed a grooved plate C, which is securely fastened to the cross-ties by means 45 of a series of spikes driven through the holes D, formed in the said plate along its sides and into the cross-ties. The grooved plate, thus firmly located on the cross-ties, receives within the groove E, the base of the rail at 50 their abutting ends. The groove E, is rectangular in form and holds the rails from lateral displacement, while a series of spikes F, having overhanging heads are driven through

suitable holes in the plate near the edge of the groove and into the ties, the heads of the 55 spikes F, projecting over the base of the rail and holding the same within the groove. This being a well known form of chair or bed plate can be conveniently used with my invention, but any method of giving the joints greater 60 security can be employed. The present invention consisting in the novel manner of making the joint, and the binding together of the overlapping ends of the rails, is accomplished by a locking bolt G. The bolt G, is 65 provided with a large flat head H, adapted to give a greater area of bearing surface to the web of the rail, and the body portion of said bolt is preferably flat and bifurcated for a portion of its length, forming the two arms 70 or branches a which are bent backward to clinch the web of the rail and be proof against being shaken loose by the wear and tear to which the rails are subjected, as is the case when nuts are used on the ends of 75 bolts. It is obvious that the bolt may be made round, hexagonal, or of any shape in cross section as may be found convenient and the ends counter-sunk to give a firmer bearing. This form of lock bolt can also be used 80 with a fish plate when the ends of the rails are not overlapping.

In Fig. 4, I have shown a double bolt, the head of which is in the form of a plate and thereby adapted to stand greater strain. 85 The locking bolt G, is inserted in the slot formed in the web of the rail, and by making the slot of greater length than the width of the bolt, sufficient provision will then be made for the expansion and contraction of 90 the rail under thermal changes.

Having thus described my invention, what I claim, and desire to secure by Letters Patent, is—

In a rail joint the combination with cor- 95 relatively recessed rails provided with corresponding apertures of a fastening device consisting of a plurality of bifurcated bolts or clips having a common head or supporting plate, substantially as specified. 100

In testimony whereof I affix my signature in presence of two subscribing witnesses.

JOHN T. EVANS.
